UNITED STATES PATENT OFFICE.

THOMAS OSBORNE HOLLAND, OF PHILADELPHIA, PENNSYLVANIA.

TOILET OUTFIT.

SPECIFICATION forming part of Letters Patent No. 692,853, dated February 11, 1902.

Application filed August 10, 1898. Serial No. 688,322. (No model.)

To all whom it may concern:

Be it known that I, THOMAS OSBORNE HOLLAND, a citizen of the United States, residing at Philadelphia, in the county of Philadelphia and State of Pennsylvania, have invented certain new and useful Improvements in Toilet Outfits; and I do hereby declare the following to be a full, clear, and exact description of the invention, such as will enable others skilled in the art to which it appertains to make and use the same.

This invention relates to shoe-cleaning outfits.

In shoe-cleaning outfits it is customary to provide a polishing-brush, a dauber, and a box containing blacking, these articles being generally closely packed in a box or holder, and unless care is taken either to envelop the bristles of the dauber in a shield, such as a piece of cloth or paper, or to wrap up the box of blacking the exterior of the box of blacking will become foul with the blacking from the dauber, and thus in use will soil the fingers and clothing of the user. To present a thoroughly-efficient outfit of this character, it is highly useful to have a shoe-horn and also a suitable implement with which mud may be scraped from the shoe. In such outfits it is not customary to provide either a shoe-horn or a mud-remover, for the reason that the space within the box is so limited that there would not be room to receive them.

It is the object of this invention, therefore, to provide a shoe-cleaning outfit in which the blacking-box will at all times be kept out of contact with the dauber and in which a shoe-horn and mud-remover may be added to the outfit without necessitating any increase in the size of the box or holder.

With this object in view the invention consists in combining with a box adapted to contain a shoe-cleaning outfit a combined shoe-horn and mud-remover detachably connected with the box and adapted for keeping the blacking-box out of contact with the bristles of the dauber.

The invention consists, further and as a new article of manufacture, in a combined shoe-horn and mud-remover provided with means for attachment to a box.

The invention consists, finally, in the various novel details of construction of a shoe-

cleaning outfit, as will be hereinafter fully described and claimed.

In the accompanying drawings, forming a part of this specification, and in which like letters of reference indicate corresponding parts, I have illustrated a form of device embodying the essential features of my invention, it being understood that other forms of embodiment thereof may be employed without departing from the spirit of the same.

In the drawings, Figure 1 is a view in perspective displaying a shoe-cleaning outfit embodying the essential ideas of my invention. Fig. 2 is a detached detail view in perspective of a combined shoe-horn and mud-remover. Fig. 3 is a sectional detail view showing a modified means of holding the guard in place within the box. Fig. 4 is a rear elevation of a modified form of shoe-horn. Fig. 5 is a fragmentary view of the end of the box, showing means for holding in place within the box the modified form of shoe-horn shown in Fig. 4.

Referring to the drawings, A designates the box or holder, which may be of any suitable material—as wood, metal, leather, or the like—and having a suitable lid (not shown) adapted to close tightly over the box, so as to prevent escape of dust or odor.

In the present embodiment of my invention I have shown two daubers A² and two brushes A³, one of which may be a stiff brush for removing dust from the shoes and the other a polishing-brush. The idea of having two daubers is to present a separate dauber for applying a tan dressing or paste to a shoe or a black dressing or paste, and to accomplish this the two boxes A⁴ will be employed containing the dressing, one resting on the other, as shown in Fig. 1. As shown, the daubers occupy a position parallel with the sides of the box, with the bristles of the daubers extending inward, and between the handles of the daubers the two brushes A³ are placed.

To keep the brushes A³ in position and also to keep the blacking-boxes and other contained articles out of contact with the hairs of the daubers, I employ a guard or shield A⁵, constituting a combined shoe-horn and mud-remover, to effect which one end of the guard is enlarged and curved in cross-section, as shown at A⁶ in Fig. 3, and the other end reduced and formed into a hook-like projection

A⁷ for removing mud from a shoe. This guard is curved in such manner as to present a bow in which the dressing-boxes will fit, as shown in Fig. 1, and the two extremities are 5 adapted to fit in between the head of the dauber and the handle of the brushes, so that the daubers will be prevented from coming into contact either with the brushes or with the dressing-boxes, and the said boxes will at 10 the same time be held from shifting in the box or holder A.

In order to hold the guard in position within the box, so that it will be effective for performing the function for which it is designed, 15 I provide at the belly of the guard a rib or projection A⁸, adapted to fit in a vertical groove or recess A⁹ in one end of the box. As here shown, the rib A⁸ is approximately dovetail-shaped in cross-section and the recess is 20 correspondingly shaped, so that when the projection on the guard is slipped into this recess the guard will be held from accidental movement. It will be understood, however, that I do not limit myself to this exact means of 25 holding the guard in position within the box, as other means may be employed, or in some instances the ends of the guard may be made to bear against the handle of the dauber with sufficient spring force to hold the guard in 30 place; but ordinarily it is preferable to employ some means for attaching the guard to the box. If preferred, instead of having the rib A⁸ dovetailed in cross-section an ordinary projection A¹⁰, as shown in Fig. 3, may extend outward from the belly of the guard and engage an opening in the end of the box. The rib or projection may be either integral 35 with the guard or may be secured thereto in any suitable manner, as by riveting or by 40 solder.

It is to be understood that when only one kind of dressing or paste is needed space is afforded to carry an emergency outfit of shoe-

laces, buttons, needles, and thread, &c. As adjunctive to the use of the guard it is to be 45 noted that this acts as a position-indicator, so that the precise manner of packing all the articles is at once apparent.

The guard or combined shoe-horn and mud-remover may be slotted transversely of its 50 width, as shown at A¹¹, Fig. 4, this slot being adapted to engage a headed pin A¹², Fig. 5, placed in one end of the box in lieu of the groove or recess A⁹.

Having thus fully described my invention, 55 what I claim as new, and desire to secure by Letters Patent of the United States, is—

1. The combination with a box adapted to contain a shoe-cleaning outfit, of a combined shoe-horn and mud-remover adapted to 60 close the box containing the blacking or dressing and to keep the same out of contact with the bristles of the dauber, substantially as described.

2. The combination with a box adapted to 65 contain a shoe-cleaning outfit, of a shoe-horn terminating at one end in a hook, constituting a mud-remover, the said shoe-horn being detachably connected with the box and adapted for keeping the blacking-box out of contact 70 with the bristles of the dauber, substantially as described.

3. The combination with a box adapted to 75 contain a shoe-cleaning outfit, embracing a brush and a dauber, of a shoe-horn likewise contained within the box and arranged to prevent contact between the bristles of the dauber and the contents of the box, and means for locking the shoe-horn to the box, substantially as described. 80

In testimony whereof I affix my signature in presence of two witnesses.

THOMAS OSBORNE HOLLAND.
